WINE RACK

John Izumi, 22W317 Glen Valley Drive,
Glen Ellyn, Ill. 60137

Filed July 18, 1972, Ser. No. 272,789

Term of patent 14 years

Int. Cl. D7—99

U.S. Cl. D7—71

FIG.1

FIG.4

FIG. 1 is a perspective view of a wine rack embodying my new design;

FIG. 2 is a front elevational view of the wine rack shown in FIG. 1;

FIG. 3 is a side elevational view of the wine rack shown in FIG. 1; and

FIG. 4 is a plain view of the wine rack shown in FIG. 1.

I claim:

The ornamental design for a wine rack, as shown and described.
